CLAIM

The ornamental design for a computer display screen with graphical user interface, as shown and described.

DESCRIPTION

FIG. 1 is a front view of a computer display screen with graphical user interface showing our new design; and, FIG. 2 is a front view of a second embodiment thereof. The unevenly spaced broken line shows a computer display screen and forms no part of the claimed design. The other broken lines show portions of the graphical user interface which form no part of the claimed design.
